UNITED STATES PATENT OFFICE

1,931,600

SWIVELED ELECTRICAL CONNECTION

Vergil W. Campbell, Hutchinson, Kans., assignor
of one-half to Verner J. Huffman, Hutchinson,
Kans.

Application May 19, 1932. Serial No. 612,319

2 Claims. (Cl. 173—324)

This invention relates to an electrical connection and it aims to provide a novel construction which will avoid tangling, undue straining and breaking of the wires, and more specifically aims to provide a construction in which the parts are swiveled together.

The more specific objects and advantages will become apparent from a consideration of the description following taken in connection with 10 accompanying drawing illustrating an operative embodiment.

In said drawing:—

Figure 1 is a view of the connection in side elevation,

15 Figure 2 is a vertical sectional view on an enlarged scale taken on the plane of line 2—2 of Figure 1.

Figure 3 is an inverted plan view of the connection.

20 Figure 4 is a cross sectional view taken on the line 4—4 of Figure 2, and

Figure 5 is a cross section taken on the line 5—5 of Figure 2.

Referring specifically to the drawing, a body 25 or section 10 of insulation has a neck 11 which extends into and is swiveled in a second body of section 12 of insulation. Extending from the body 12 are metallic conductor prongs 13 and 14, respectively, preferably made in a single piece 30 and having tangs 15 and 16 by means of which they are detachably bolted as at 17 and 18 to the body 12. Prong 13 at the inner end has a ring 19 integral therewith and disposed at a right angle thereto. After the prong 13 is set 35 cured in place, but before the prong 14 is mounted, a conductor sleeve 20 is secured to the neck 11 in any suitable manner, for instance, by friction, and the same has an annular flange at 21 which underlaps the ring 19. Thus the body 40 10 carries the sleeve 20 and flange 21 constantly moved in contact with the ring 19. A conductor strip 22 is formed as a tongue on sleeve 20 and secured in any suitable manner as by means of screw 23 to the body 10. One of the feed wires 45 for the current is shown at 25 and is fastened in place in contact with strip 22 by means of the screw 23. The companion conductor is shown at 26 and is secured by a screw 27 in contact with a conductor 28 which terminates centrally of 50 the plug 10 in an enlargement 29 at the base of an extension 30 of neck 11. The outer surface of the enlargement 29 is preferably spherical. The prong 14 has an inward extension at 31, preferably of less thickness than the remainder 55 of the prong to afford resilience, and which extension 31 is in constant wiping contact with the enlargement 29. As a result the wires will not become twisted since movement of body 10 relative to body 12 maintains electrical contact 60 to the flanges 19 and 21 and enlargement 29 and

contact 31, notwithstanding such parts move relatively to each other.

An operating sleeve 32 is preferably screwed as at 33 to the body 12 and the same has an outwardly extending flange as at 34 to form an 65 abutment for engagement by the fingers to facilitate removal and application of the device.

It is obvious that the swivel connection may be used generally in connection with electrical appliances and especially in connection with a 70 telephone receiver.

Various changes may be made provided they fall within the spirit and scope of the invention.

What is claimed is:—

1. A connection of the class described comprising a body section, conducting elements secured to the body section, one of the elements terminating in a ring, the other element having a resilient extension spaced outwardly of the ring, a section of insulation abutting the body 75 section and having a neck extending thereinto, a conducting sleeve carried by said neck and having a flange underlapping said ring, a conductor strip carried by the section of insulation in conducting relation to said sleeve, a conductor member 80 carried by the section of insulation extending through said neck and engageable by said resilient extension, and an extension on said neck, said conductor member having a spherical surface at the base of said extension directly engageable by said resilient extension. 90

2. A connection of the class described comprising a body section, conducting elements secured to the body section, one of the elements terminating in a ring, the other element having a resilient extension spaced outwardly of the ring, a section of insulation abutting the first 95 mentioned section and having a neck extending thereinto, a conducting sleeve carried by said neck and having a flange underlapping said ring, a conductor strip carried by the section of insulation in conducting relation to said sleeve, a conductor member carried by the section of insulation extending through said neck and engageable by said resilient extension, an extension on said neck, said conductor member having a spherical surface at the base of said extension directly engageable by said resilient extension, and an operating sleeve detachably secured to the first mentioned section and enclosing the 100 second mentioned section, said sleeve having an outwardly extending flange adjacent its free end. 110
